101,303

DESIGN FOR A TEXTILE FABRIC OR SIMILAR ARTICLE OF MANUFACTURE

John F. Gaul, Jr., Clifton, N. J., assignor to
Botany Worsted Mills, Passaic, N. J., a corpo-
ration of New Jersey

Application June 19, 1936, Serial No. 63,389

Term of patent 14 years

To all whom it may concern:

Be it known that I, John F. Gaul, Jr., a citizen of the United States of America, residing at No. 1110 Van Houten Avenue, in the town of Clifton, State of New Jersey, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

The characteristic feature of the present design resides in a plain base fabric, which is loosely woven, resulting in a rough or crepe-like appear-

ance, series of vertically disposed lines or ribs having a multiplicity of thickened threads arranged over the surface of the fabric but disposed upon, and lengthwise of, said vertical lines or ribs, and groups of threads intermediate definite series of said ribs, said threads being of contrasting color and of substantially equal length and separated by substantially equal spaces vertically of the fabric.

I claim:

The ornamental design for a textile fabric or similar article of manufacture substantially as shown and described.

JOHN F. GAUL, JR.
